DRIFTING VALVE

Filed July 26, 1926

UNITED STATES PATENT OFFICE

MARK MCCOMAS, OF DENISON, TEXAS, ASSIGNOR, BY MESNE ASSIGNMENTS, OF
ONE-HALF TO C. E. STANTON, OF DALLAS, TEXAS

DRIFTING VALVE

Application filed July 26, 1926. Serial No. 125,014.

This invention relates to a device especially designed for use in connection with locomotives, the primary object of the invention being to provide means for directing a quantity of steam to the valves, dry pipe and movable parts of a locomotive to cushion the movable parts while the engine is working or drifting.

A still further object of the invention is to provide means for supplying steam to the cylinders and valve chambers at all times, to maintain the proper temperature within the cylinders and valve chambers to reduce condensation to the minimum.

A further object of the invention is to provide a device of this character which will be automatic in its operation and one which will not function when the locomotive is running at low rates of speed, or is brought to a stop.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is an elevational view illustrating a device constructed in accordance with the invention as installed on a locomotive.

Figure 2 is a view illustrating the device on an enlarged scale, the valve members thereof being shown in section.

Figure 3 is an enlarged sectional view through the drifting valve.

Referring to the drawings in detail, the reference character 5 indicates the usual engine cylinder in which the pistons operate, and the reference character 6 indicates a valve chamber for controlling the passage of steam in the usual way, to the cylinder 5.

The device forming the essence of the present invention includes a pipe 7 which is in communication with the interior of the cylinder 5 as shown by Figure 1. This pipe 7

is connected with the pipe 8 in which the

check valve 9 is positioned, the pipe 8 having connection with the storage tank 10 in such a way that steam may be stored in the tank 10 and will be prevented from returning to the cylinder 5.

Pipe 11 communicates with one end of the storage tank 10 and is connected with pipe 12 by means of the elbow 13, which pipe 12 connects with the substantially short pipe 14 which in turn, communicates with the interior of the valve housing 15. This valve housing 15 is supported by means of the bracket 16 which is secured to the boiler casting 17 of the locomotive, and as shown, is supplied with a removable head 18 having a depression forming a seat for one end of the coiled spring 19.

Operating within the valve housing is a piston 20 which is normally urged to the limit of its forward movement by means of the coiled spring 19, which is shown as bearing against the piston 20.

The reference character 21 indicates the piston rod which extends through one end of the valve housing and connects with the piston 20, the rod 21 also passing through the bonnet 22 and steam dome, as clearly shown by Figure 2. The inner end of the rod 21 has pivotal connection with the drifting valve 23 adapted to engage the valve seat 24 that is supported within the throttle box 25 so that movement of the valve to its open position will allow steam to pass from the dome through drifting valve into throttle box, where it may find its way into the valve chamber and cylinders of the locomotive.

The storage tank is supplied with an exhaust opening 26 which is adapted to exhaust steam from the storage tank when the engine is running at a low rate of speed, or is stopped, to relieve the pressure within the storage tank and allow the spring 19 to act on the piston 20 to close the valve 23.

In the operation of the device it will be seen that when the engine is running, steam will pass through the pipes leading from the cylinder 5 to the storage tank where the steam will collect, the pressure of the steam acting on the piston 20 to overcome the tension of the spring 19.

100

As the spring 19 is compressed by the rearward movement of the piston 20, valve 23 will be moved to its open position to allow steam to pass to the valve chamber and cylinder cushioning the moving parts.

When the engine is drifting, sufficient compression is developed in the front end of the steam cylinder to act on the piston 20 to unseat the valve 23, allowing steam from the boiler to pass into the dry pipe and hence into the valves and cylinders of the locomotive furnishing steam to maintain the proper temperature in the cylinders and valve chambers at all times.

15 I claim:

An auxiliary valve for automatically releasing steam from the throttle box to the cylinders of a locomotive, comprising a valve body mounted within the throttle box and communicating with the interior thereof, a valve operating in the valve body to normally close the valve body, a rod to which the valve is connected, a piston on one end of the rod, a housing in which the piston operates, a spring in the housing for normally urging the piston in one direction to seat the valve, a pipe extending from one end of an engine cylinder and communicating with the valve housing, and a storage tank in the pipe line for automatically storing up steam to operate the piston and valve against the tension of the spring to direct a quantity of steam to the valves of the engine.

35 In testimony that I claim the foregoing as my own, I have hereto affixed my signature.

MARK McCOMAS.
